UNITED STATES PATENT OFFICE.

WILLIAM KOCH, OF NEW YORK, N. Y.

NUMBERING-MACHINE.

SPECIFICATION forming part of Letters Patent No. 398,624, dated February 26, 1889.

Application filed November 10, 1887. Serial No. 254,773. (No model.)

To all whom it may concern:

Be it known that I, WILLIAM KOCH, of the city, county, and State of New York, have invented certain new and useful Improvements 5 in Consecutive-Numbering Machines; and I do hereby declare that the following is a full and exact description thereof, reference being had to the accompanying drawings, and to the letters of reference marked thereon, making 10 a part of this specification, in which—

Figure 1 is a front elevation of my improved consecutive-numbering machine; Fig. 2, a rear elevation thereof; Fig. 3, a vertical section in line $x-x$ of Fig. 1; Fig. 4, a similar section 15 showing the numbering-head forced down in position for imprint; Fig. 5, a detached transverse section of the pivoted pin actuating the numbering-wheels, taken longitudinally through its pivotal axis; Fig. 6, a transverse section in line $z-z$ of Fig. 5, and 20 Figs. 7 to 9 diagrams illustrating the several positions of said actuating-pin during the movements of the numbering-head.

My invention relates to the construction 25 and arrangement of a self-inking consecutive-numbering head actuated by the vertical movements of a rod carrying said head.

It has for its object to simplify the construction of the head by reducing the number 30 of its parts, to render its action positive and independent of springs, to lock its movements so that it shall not be possible for either of the numbering-wheels to overthrow or to turn otherwise than in proper order.

It consists in the construction and combination 35 of mechanism hereinafter described, and particularly set forth in the claims.

In the accompanying drawings, A represents the frame in which the numbering-head 40 is mounted and permitted to play, said frame being adapted, by means of a bracket and setscrew or other adequate device, to be made fast to a table or other object for support. This frame A is constructed in usual form of 45 two side plates, a a' , an upper connecting-bar, B, and a central collar, C, which serves as a bearing for the rod D, carrying the numbering-head. The rod D is fitted to move freely through the collar C, which is sufficiently 50 extended to afford adequate support and bearing for the rod in its reciprocating

movements therein, and to its lower end is secured a frame consisting of a cross bar or plate, E, from which depend two side plates, F F, to afford bearings for the shafts of the 55 numbering-wheels and the spur-wheels or pinions of the head.

The numbering-wheels 1 2 3 4 are mounted upon a fixed shaft, G, supported at either end in the side plates F F, near the lower end 60 thereof, so as to revolve freely thereon side by side, each independently of the other, and to project below said side plates. Each numbering-wheel bears upon its periphery, at equal distances apart, suitable type representing 65 the nine digits and a cipher, and the intervals between the type are cut out to form notches m m m , adapted to be engaged severally by the teeth n of spur or pinion wheels geared thereto to actuate them. The necessity 70 of secondary pinions or spur-wheels is thereby obviated.

The ends of the shaft G are made to project through the side plates F F far enough to pass into longitudinal grooves j j in the 75 side plates a a' of the supporting-frame, (see dotted lines Fig. 1,) to guide the head in its reciprocating movements.

A separate spur-wheel or pinion, H, is provided for each numbering-wheel, and these 80 spur-wheels are all mounted side by side upon a shaft, I, secured at either end in the side plates F F, parallel with and at a suitable distance above and in front of the shaft G, so that the teeth upon said spur-wheels mesh 85 into the notches of the numbering-wheels. Each pinion H is fitted with ten teeth, n n , to correspond with the number of notches m m in the numbering-wheel, to which it is geared, so that the latter will make a complete revolution at each complete revolution of the former. One tooth, i , (see Fig. 1,) upon each 90 spur-wheel is made so wide that when it engages the numbering-wheel to which the spur-wheel is geared it will also overlap and engage the numbering-wheel next on the left, so that both wheels will be turned by the same tooth and the second wheel moved one step at each revolution of the first.

The units-wheel 1 is moved one step at each 100 upward movement of the numbering-head by means of a finger, K, projecting from a sleeve,

at the bottom of the sleeve K', mounted to rotate upon a stud, L, projecting horizontally from the side plate a' of the supporting-frame A, parallel with the shafts G and I, and in front of and below the latter, so that the finger K, when held in a horizontal position, shall engage the teeth of the spur-wheel geared to the units-wheel. The finger K is brought automatically to its normal horizontal position by means of a spiral spring, R, interposed in a suitable recess between the sleeve K' and stud L, upon which it turns, and is stopped in said position by means of a tooth, O, projecting from the end of a collar, O', fixed upon the stud L, into a recess, Q, cut in the adjacent end of the sleeve K'. (See Fig. 1.)

The recess Q is so disposed that when the numbering-head is lowered so as to bring a tooth, n, of the spur-wheel H into contact with the finger K the latter will be free to give by the turning of the sleeve K', although so soon as the tooth n has passed down out of engagement with said finger K the latter will, under the influence of the spring R, turn back to its first position in readiness to engage the same tooth n when the numbering-head is elevated. As the head is lifted, the finger n, striking the tooth K, which is held fast in this direction, will be made thereby to turn the spur-wheel H, and with it the units-wheel, one step, so that the units-wheel will thus be actuated one step after each impression made thereby by reason of its being carried down upon the paper beneath it.

35 A reverse movement of the several numbering-wheels is prevented in the customary manner by means of pawls S S, pivoted upon a cross-bar, S', to drop into engagement with the teeth of the spur-wheels H H, geared to the numbering-wheels, this engagement being enforced by springs S² S².

All the numbering-wheels other than the units-wheel are at all times positively locked, so as to be fixed in their positions excepting 45 at the moment when the projecting tooth of the units-wheel is brought into position to actuate the tens-wheel, being released only during the interval in which the movement 50 of the tens-wheel occurs. This positive lock of the wheels is accomplished by means of a dog, consisting of a plate, 12, (see Figs. 2, 3, and 4,) made wide enough to overlap all the 55 numbering-wheels excepting the units-wheel, and which is pivoted at one edge upon a transverse rod, 13, extending across the head parallel with the axis of the wheel. The free edge of the plate or dog is suitably bent and shaped to engage the notches m m in said 60 wheels, and it drops into said notches automatically by its weight, so as to engage them all simultaneously.

The edge of the plate 12 is prevented from rising out of said notches, and is thereby made to hold and lock them positively by means of 65 an arm, 14, projecting from one end of the pivotal edge of the plate radially in the opposite direction in position to bear upon the

periphery of a circular disk, 15, made fast to the outer face of the spur-wheel H, actuating the units-wheel. So long as the end of the 70 arm 14 bears upon the concentric periphery of said disk the dog 12 is held fast in its engagement with the numbering-wheels to lock them.

The release of the dog at the moment the 75 units-wheel is in position to actuate the tens-wheel is permitted by means of a circular notch, 16, cut in the periphery of the disk 15 in such position as to allow the arm 14 to move inward thereon at the desired moment. The 80 dog is then left free to slip out of the notches and to remain free long enough to permit the numbering-wheels, or any one or more of them, to turn forward one step in unison with the one step of the units-wheel. The next succeeding step of the units-wheels, by carrying the notch 16 away from the end of the arm 14, 85 will again lift it, and thereby operate, in manner as described, to lock the dog.

The numbering-wheels are inked after each 90 impression by means of an inking-pad, T, fitted upon a swinging bracket, U, pivoted to a cross-bar, U', in the frame A, so as to be free to swing under the wheels and into contact with the type thereon, when they are elevated 95 to their highest position.

The movement of the swinging bracket and its pad is produced and controlled by a double link, V, pivoted at one end to a cross-bar, V', upon the bracket and at the other to a parallel 100 cross-bar, V², secured to the side plates, F F, of the numbering-head. The link is so adjusted in length and the pivotal bars V' and V², upon which it swings, so located that when the numbering-head is elevated the link is 105 brought nearly to a vertical plane, drawing the bracket inward, so as to carry its pad T under and into contact with the lowermost type on the numbering-wheels, as shown in Figs. 1, 2, and 3. When, however, the numbering-head is depressed, the link is thrown out to and beyond a horizontal plane, as shown in Fig. 4, thereby causing the bracket to swing out from the head and withdraw the pad wholly clear of the numbering-wheels.

110 The connection of the numbering-machine with an adding or check or printing machine is effected by means of a pivoted lever, 20, oscillated by the movements of the adding or printing machine, and whose free end is passed through a slot, 21, in the upper end of the rod D. Where the movements of the lever 20 are positive and invariable, I insert in the head of the rod D a set-screw, 22, whereby the stroke of the rod D, actuated by the lever 20, may be 115 adjusted, so that as the inking-pad wears away its contact with the numbering-wheels after each impression therefrom may be maintained by shortening the stroke of the rod D, this result being obtained by screwing inward 120 the set-screw 22, so as to reduce the length of the slot 21.

125 The inking-pad consists of an absorbent layer of one or more thicknesses of suitable

material adapted to retain a proper supply of ink, and which is secured in any suitable manner upon a metallic plate, U³.

In the operation of the machine, when the numbering-head is forced downward by pressure upon the rod D, the inking-pad will, as the head descends, swing out from under the numbering-wheels, leaving them clear to make their impression upon the surface to which they are applied. As this downward movement takes place the horizontal tooth on the first spur-wheel H will strike the actuating-finger K, carried by the sleeve K' on the fixed stud L; but said sleeve K', being free to revolve upon the stud in the direction of the movement, will simply turn the finger K out of the way, so that the spur-wheel may freely pass, and will then turn back automatically to its first position under the influence of its spring. Upon the return upward movement of the head, however, when said horizontal projecting tooth of the spur-wheel H strikes the finger K, the finger, being prevented from turning upward, will operate to move the spur-wheel one step, which said movement will be communicated to the units-wheel geared thereto. Thus at each upward movement of the head after each impression produced therewith the units-wheel will be automatically turned far enough to change the number.

At each complete revolution of the units-wheel it will move the tens-wheel one step by means of the customary device for this purpose, hereinbefore described, and at the moment this movement of the tens-wheel is effected the locking-dog 12 is freed from the numbering-wheels to permit them to turn by the passage of the end of the arm 14 into the notch 16 in the periphery of the locking-disk 15, as above described.

It is evident that spur-wheels or pinions meshing directly with peripherally-cogged type-wheels may be employed in adding-machines as well as numbering-heads to avoid extra gears, and I contemplate the use thereof in all such machines.

I claim as my invention--

1. The combination, in a numbering-machine, of an outer stationary frame, an inner movable frame reciprocating therein, parallel shafts mounted in said inner movable frame, a series of one or more peripherally-cogged numbering-wheels revolving upon one of said shafts and each bearing type upon their cogs,

corresponding spur-wheels revolving upon the other shaft and gearing severally with said cogged numbering-wheels, a yielding finger projecting from the stationary frame in position to be engaged by a tooth of the first spur-wheel at each reciprocating movement of the inner frame, a stop preventing said finger from yielding under the pressure of the tooth as the frame moves inward, and a spring actuating said finger to carry it to its normal position, all substantially in the manner and for the purpose herein set forth. 55

2. The combination, in a numbering-machine, of an outer stationary frame, an inner movable frame reciprocating therein, parallel shafts mounted in said inner movable frame, 70 a series of cog-wheels having type upon the cogs and revolving upon one of said shafts, a corresponding series of spur-wheels revolving upon the other shaft and gearing severally with said type-wheels, a single tooth projecting laterally from each spur-wheel to engage the next adjacent type-wheel at each complete revolution, a disk upon the outer side of the first of said spur-wheels, said disk having a single notch in its periphery, a wide dog pivoted to the movable frame upon an axis parallel with the axial shafts of the spur and type wheels, and which engages simultaneously all the type-wheels excepting the first, and an arm projecting from the dog into contact with the periphery of the disk, all substantially in the manner and for the purpose herein set forth. 75

3. The combination, with the swinging inking-pad bracket U, pivoted to the fixed frame A, 90 the reciprocating frame traversing in said fixed frame, and the numbering-wheels mounted in said reciprocating frame, of the link V, pivoted to the swinging bracket-frame and to the frame carrying the numbering-wheels, 95 whereby the movements of the head operate to swing the bracket and its pad in and out of contact with the numbering-wheels, all substantially in the manner and for the purpose herein set forth. 100

In testimony whereof I have signed my name to this specification in the presence of two subscribing witnesses.

WILLIAM KOCH.
